US00D928020S

(12) United States Design Patent (10) Patent No.: US D928,020 S
Raftis (45) Date of Patent: * Aug. 17, 2021

(54) PENDANT

(71) Applicant: Nicholas Dennis Raftis, Alvin, TX (US)

(72) Inventor: Nicholas Dennis Raftis, Alvin, TX (US)

() Term: 15 Years

(21) Appl. No.: 29/766,047

(22) Filed: Jan. 13, 2021

Related U.S. Application Data

(62) Division of application No. 29/746,551, filed on Aug. 14, 2020.

(51) LOC (13) Cl. 11-01

(52) U.S. Cl.

USPC D11/81

(58) Field of Classification Search

USPC D11/1, 3, 31, 34, 39, 41, 78.1, 79, 81, 2, D11/4, 6, 7, 9, 10, 11, 12, 13, 14, 15, 16, D11/17, 18, 20, 26-30, 35-38, 42-49, 57, D11/58, 70, 75-78, 82, 85, 86, 89-92, 93, D11/99, 108, 40, 121, 122, 125, 131, D11/133; D99/17-27; D3/207, 211; D30/155
